UNITED STATES PATENT OFFICE

PHILIP C. DONNER, OF SUMMIT, NEW JERSEY, ASSIGNOR TO THE CHAPAL DONNER CORPORATION, OF NEWARK, NEW JERSEY, A CORPORATION OF NEW JERSEY

HAT MAKING MACHINERY

Application filed August 22, 1930. Serial No. 477,055.

This invention relates to improvements in hat-making machinery, and the invention has reference, more particularly, to improvements in that type of hat body stretching machines known to the industry as tip-stretchers.

In tip-stretching machines as heretofore constructed and used, the clamp rings of the hat body supporting cage, when in operative relation to the stretching fingers are maintained immovable from axial or vertical alignment with the path of reciprocable movement of the stretching fingers. As a consequence of this fixed relation, undue stretching strains are applied to the tip or apex portion of the hat body, with the result that the stretching operation tends to unduly deform such portion of the hat body, causing an undesirable bulge at the apex of the same, termed in the industry a "button". Such defective formation is difficult and sometimes even impossible to cure when submitting the stretched hat body to subsequent blocking, shaping and finishing operations, therefore giving rise to loss and over production of "seconds," all of which is wasteful and highly undesirable.

It is the principal object of this invention to provide improvements in the construction and mode of operation of tip stretching machines whereby the formation of "buttons" during the stretching operations is avoided, and whereby the stretching effects are more evenly and uniformly applied to the hat body, with the result that a superior product is obtained with minimum risk or waste. To this end, the invention comprises the provision of means for imparting to the clamp rings of the hat body supporting cage of a tip stretching machine, and the hat body gripped thereby, an oscillatory movement about the vertical axis thereof when rotated beneath the vertically reciprocated stretching fingers of the machine to subject the hat body to the stretching action thereof.

Other objects of this invention, not at this time more particularly enumerated, will be clearly understood from the following detailed description of the same.

An illustrative embodiment of this invention is shown in the accompanying drawings, in which:—

Figure 1 is a front elevation of a tip stretcher machine provided with the improved features of this invention; Figure 2 is a fragmentary vertical section of the same, taken on line 2—2 in Figure 1, and drawn on a somewhat enlarged scale; and Figure 3 is another fragmentary vertical section, taken on line 3—3 in Figure 2.

Similar characters of reference are employed in all of the hereinabove described views, to indicate corresponding parts.

Referring to said drawings, the reference character 5 indicates the side frames of the machine, which are laterally spaced apart and suitably interconnected to provide the supporting framework for the operating mechanism of the machine. Journaled to extend laterally through the lower portions of said side frames 5 is a suitably driven main shaft 6.

Arranged at the upper end of the machine is a cross-head 7 supported for vertical reciprocation by slide rods 8 which are slidably mounted in connection with said side frames 5, and the lower ends of which are connected with a lower cross-head 9. Vertical reciprocable movement is imparted to said lower cross-head 9, slide-rods 8 and upper cross-head 7 by eccentrics 10 actuated by the main shaft 6; the connecting rods 11 of said eccentrics being pivotally coupled with said lower cross-head 9.

Centrally depending from said upper cross-head 7 is a threaded column 12 on which are adjustably supported the radially arranged downwardly and outwardly divergent stretcher fingers 13, in the manner commonly employed in tip-stretching machines.

Suitably mounted in the lower portion of the machine, in axial alignment with the column 12 and its stretcher fingers 13, is a vertically movable post 14 on the upper end of which is carried the hat body supporting cage structure to be presently described.

Journaled to extend laterally through the lower portions of said side frames 5, behind the main shaft 6, is a secondary drive shaft 15 on which is fixed a lift cam 16, which op-

erates to raise and lower the post 14. Suitably fixed in the rearward portion of the machine framework is a fulcrum shaft 17 on which is pivoted a forwardly extending lever frame 18, the latter being above said lift cam. Mounted between the arms of said lever frame 18 is an anti-friction roller which is engaged by said lift-cam 16. Fixed on the lower portion of said post 14 is a collar 19 having laterally and oppositely projecting studs 20, and interconnected between said studs and the forward free ends of said lever frame arms are links 21.

Said secondary shaft 15 is driven from the main shaft 6 as follows:

Journalized in and between the side frames 5 is a counter shaft 22. Said counter shaft 22 is driven at desired speed ratio from said main shaft 6 by intermediate variable speed pulley and belt transmission 23, or in any other well-known manner. Connected in the line of said counter shaft 22 is a suitable clutch means 24 for starting and stopping the driven section 22' of said counter shaft 22 at will. Fixed on the driven section 22' of said counter shaft is a pinion 25, which drives a reduction gearing 26 with which said secondary shaft 15 is connected. The above described transmission mechanism and the lift-cam 16 for operating the supporting post 14 which carries the hat body supporting cage of the machine is all typical of tip stretching machines as heretofore used and will be familiar to those skilled in the art in which such machines are utilized.

The hat body supporting cage comprises a sleeve or hub 27 which is mounted for limited sliding movement on the upper end of said post 14. Connected with said sleeve or hub is a horizontal base plate 28 from the upper side of which rise the arcuate cage members 29, the same being radial to the vertical axis of the post 14 and arranged to meet at their upper ends so as to provide a hat tip support. The spaces between adjacent cage members 29 provide recesses in which the stretcher fingers 13 of the machine work in the usual manner. The lower end of said sleeve or hub 27 possesses a diametrically enlarged portion 30, to the opposite sides of which are pivotally connected links 31. Fixed on said post 14 below said sleeve or hub 27 is a collar 32 having a fulcrum arm 33 for pivotally mounting a lever means 34. The links 31 are pivotally connected with the inner end of said lever means 34, and a weight 35 is suspended by the rod 36 from the outer end of said lever means. The weighted lever means serves to yieldably bias said hat body supporting cage to its upwardly moved position on said post 14, in the manner usual to tip stretching machines.

Associated with said hat body supporting cage, and mounted for rotation and oscillation relative thereto by means of a universal

mounting to be presently described, is an annular carrier ring 37, which is provided on its upper outer marginal portion with a seat 38 to receive and hold a male clamp ring 39 disposed to surround the base plate 28 of said hat body supporting cage. Said clamp ring is preferably provided with a resilient facing member 40 of suitable material, such e. g. as rubber. The universal mounting to arrange said male clamp ring for rotation and oscillation relative to said hat body supporting cage, comprises a hub 41 rotatable on said sleeve or hub 27 above its enlarged portion 30. Pivoted to said hub 41, on a horizontal axis transverse to the axis of said post 14, is a yoke 42 having diametrically oppositely extending arms 43. Connected with said hub 41 are perforate ears 44 parallel to said yoke arms 43. Oppositely extending links 45 are pivotally connected by their inner ends to said ears 44 to extend parallel to said yoke arms 43. Pivotally connected by their lower ends to said yoke arms 43 are vertical links 46, to which the outer ends of said links 45 are also pivotally connected. The upper ends of said vertical links 46 terminate in ball joint elements 47 which pivotally engage in sockets 48 provided in the under side of said carrier ring 37, thus providing an axis of oscillatory movement for the latter at right angles to the axis of oscillatory movement of said yoke member 42. It will thus be obvious that the male clamp ring, when rotated is also capable of a universal oscillatory movement about the axis of said post 14.

Cooperative with said male clamp ring 39 is a female clamping ring 49, which is operatively supported by a rotatable and oscillatable carrier ring 50. Connected with the side frames 5 of the machine are bearing housings 51, in which are mounted vertically movable bearing blocks 52 to journal the trunnions 53 of a bearing yoke 54 in which said carrier ring is rotatably supported. Said bearing blocks 52 are yieldably pressed by compression springs 52' toward the lower ends of the ways provided therefor in the bearing housings 51, thus yieldably biasing said carrier ring 50 and its female clamp ring 49 toward said male clamp ring 39.

The means for imparting rotary movement to said carrier ring 50 and its female clamping ring 49, comprises a horizontally disposed ring bearing 55 rigidly secured to the side frames 5 by brackets 56. Said ring bearing 55 is provided with an upstanding annular bearing flange 56 on which is journaled a ring gear 57. Said ring gear 57 is provided on its upper side with an inwardly projecting flange 58 which overhangs said bearing flange 56. Interconnected between said ring gear flange 58 and said carrier ring 50 are coupling connections, preferably of yieldable form, such e. g. as the spring couplers 59. The means for driving said ring 130

gear preferably comprise a vertical shaft 60 driven from said secondary drive shaft 15 by the gearing 61, and secured to the upper end of said vertical shaft 60 is a spur gear 62 to mesh with and drive said ring gear 57.

The means for imparting oscillatory movement to the carrier ring 50 and the female clamp ring 49 comprises an outwardly projecting arm 63 connected with said bearing yoke 54, the same extending rearwardly of the machine. Pivottally mounted on a bracket 64 supported by the framework of the machine is a rocking lever 65, the inner end of which is pivotally connected with the free end of said arm 63 by means of a link 66. Pivottally mounted on a fixed fulcrum bracket 67, in the lower part of the machine, is an actuating lever 68, the outer end of which is coupled with the outer end of said rocking lever 65 by a connecting rod 69. Fixed on said secondary drive shaft 15, so as to be rotated thereby, is a cam wheel 70 having in its face a suitably shaped cam race 71. The inner end of said actuating lever 68 is provided with a roller stud 72 to operatively engage in said cam race 71.

Supported by the upper end of said post 14, within the hat body supporting cage, is a steam nozzle 73 connected with a control valve 74 by the flexible conduit 75, said control valve 74 being in turn connected with a steam supply pipe 76. The opening and closing of the control valve is attained by any suitable actuating means, preferably operated by the lever frame 18 through the connecting rod 77 in the manner usual to tip stretching machines, and whereby steam is discharged from the nozzle 73 to soften a hat body supported on the hat body supporting cage when subjected to the stretching action of the reciprocated stretching fingers 13.

In the operation of the tip stretching machine, a hat body B (see Fig. 2) is engaged over the supporting cage while the same is lowered to inactive position. When the hat body B is thus mounted, the clutch means 24 is manipulated to drive the secondary drive shaft 15 from the main shaft 6 through the intermediate transmission mechanism, of which said clutch means forms a part. As the secondary drive shaft 15 turns, the lift cam 16 will operate the lever frame 18 to elevate the post 14, whereby the hat body supporting cage and the hat body B thereon is raised into operative relation to the vertically reciprocating stretcher fingers 13. The marginal portions of the hat body B are disposed over the male clamp ring 39, so that as the hat body is carried upwardly, such marginal portions will be carried into contact with the female clamp ring 49, so as to be gripped between the same and said male clamp ring. To assure snug fitting of the hat body on the supporting cage, the male

clamp ring 39 will initially yield to the pressure of the female clamp ring 49 to the extent of downward movement of the sleeve or hub 27 on the post 14 against the biasing pulls of the weight 35, and until said sleeve or hub 27 is stopped against the fixed collar 32, thereby assuring that the hat body will be pulled smoothly and evenly over the supporting cage members, and then finally gripped between the clamp rings 39 and 49, as the limit of upward movement of post 14 is approached and the upward thrust of the male clamp ring 39 is opposed by the compression springs 52' of the female clamp ring carrying means.

The operation of the secondary drive shaft 15 in turn drives the ring gear 57, the rotary motion of which is transmitted through the coupling springs 59 to the carrier ring 50 and female clamp ring 49, which thereupon rotates in horizontal plane causing a rotation of the gripped hat body B and male clamp ring 39. Accompanying this rotative movement of the clamp rings and hat body relative to the hat body supporting cage, a rocking movement is imparted thereto through the cam actuated rocking lever 65. The combined rotating and rocking movement thus imparted to the hat body B is oscillatory in character, and is permitted by reason of the universal mounting by which the male clamp ring 39 is supported. The oscillatory movement thus imparted to the hat body B shifts the same back and forth or from side to side over the relatively stationary hat body supporting cage, so that the tip or apex of the hat body B is shifted from side to side or back and forth, while undergoing the stretching treatment exercised thereon by the vertically reciprocated stretching fingers 13. By reason of such shifting the stretching strains are not unduly concentrated at the tip or apex of the hat body but are more evenly distributed from such tip or apex toward the sides thereof, and consequently tendency to unduly bulge the tip or apex portions, with resultant formation of undesired "buttons" in the stretched hat bodies is entirely eliminated, and a more perfectly and uniformly stretched hat body is attained.

As many changes could be made in the above described improved construction of hat tip stretching machine, and many apparently widely different embodiments of this invention could be made without departing from the scope thereof, it is intended that all matter contained in the above description or shown in the accompanying drawings shall be interpreted as illustrative and not in a limiting sense.

What is claimed is:—

1. In a machine of the kind described, vertically reciprocable stretching fingers, a supporting cage to hold a hat body subject to

the action of said stretching fingers, a female clamp means, means to rotate said female clamp means about the vertical axis of the supported hat body engaged therewith to turn the latter on such axis, means to simultaneously rock said female clamp means on a transverse horizontal axis at right angles to the axis of rotation to oscillatorially shift the supported hat body during rotation thereof, a male clamp means cooperative with said female clamp means to grip the hat body in operative connection therewith, means to mount said male clamp means for rotation about the vertical axis of said supported hat body, and a universal connection between said latter means and said male clamp means.

2. In a machine of the kind described, vertically reciprocable stretching fingers, a supporting cage having an axial sleeve, a carrying post on which said sleeve is mounted, a hub rotatable on said sleeve beneath said supporting cage, a male clamp ring around the base of said supporting cage, a universal coupling means intermediate said hub and said male clamp ring whereby the latter may turn about the vertical axis of supporting cage and at the same time oscillate laterally, a female clamp ring with which said male clamp ring cooperates, a carrier ring for said female clamp ring, a yoke-frame to support said carrier ring, said yoke-frame being pivoted to oscillate on an axis transverse to the vertical axis of said supporting cage, said carrier ring being freely rotatable in said yoke frame, means to transmit rotary motion to said carrier ring, and means to oscillate said yoke frame during rotation of said carrier ring.

3. In a machine of the kind described, vertically reciprocable stretching fingers, a supporting cage having an axial sleeve, a carrying post on which said sleeve is mounted, a hub rotatable on said sleeve beneath said supporting cage, a male clamp ring around the base of said supporting cage, a universal coupling means intermediate said hub and said male clamp ring whereby the latter may turn about the vertical axis of supporting cage and at the same time oscillate laterally, a female clamp ring with which said male clamp ring cooperates, a carrier ring for said female clamp ring, a yoke-frame to support said carrier ring, said yoke-frame being pivoted to oscillate on an axis transverse to the vertical axis of said supporting cage, said carrier ring being freely rotatable in said yoke frame, means to transmit rotary motion to said carrier ring, and means to oscillate said yoke frame during rotation of said carrier ring, said latter means comprising a rocking lever, said yoke frame having an outward projecting arm with which one end of said rocking lever is pivotally connected, and cam controlled actuating means connected 65 with the other end of said rocking lever.

4. In a machine of the kind described, vertically reciprocable stretching fingers, a cage to support a hat body subject to the action of said stretching fingers, means to clamp the brim portions of a hat body when supported on said cage, means to rotate said clamp means about the vertical axis of said cage to turn the supported hat body, and means to rock said clamp means during rotation thereof to move the tip of the hat body laterally back and forth over the apex of the cage.

5. In a machine of the kind described, vertically reciprocable stretching fingers, a supporting cage on which the hat body is engaged subject to the action of said stretching fingers, cooperative clamp rings to grip the hat body when supported by said cage, and cooperating means for rotating and rocking said clamp rings whereby the latter are adapted to turn the hat body axially while at the same time shifting said hat body back and forth transversely of the axis of said cage.

In testimony, that I claim the invention set forth above I have hereunto set my hand this 16th day of August, 1930.

PHILIP C. DONNER.
